UNITED STATES PATENT OFFICE.

JOHN O. BARDILL, OF DESLOGE, MISSOURI.

ORE-CONCENTRATING-TABLE LAUNDER.

SPECIFICATION forming part of Letters Patent No. 720,774, dated February 17, 1903.

Application filed October 27, 1902. Serial No. 129,003. (No model.)

To all whom it may concern:

Be it known that I, JOHN O. BARDILL, a citizen of the United States, residing at Desloge, in the county of St. Francois and State of Missouri, have invented certain new and useful Improvements in Ore-Concentrating-Table Launderers, of which the following is a full, clear, and exact description, reference being had to the accompanying drawings, forming part of this specification.

My invention relates to a launder for receiving and separating mineral from ore-pulp, the object of the invention being to provide a construction in which the mineral may be separated from the ore-pulp and discharged from the concentrating-table in a practically clean condition and the middlings may be graded and discharged separately from the tailings of the pulp and also in which the grading of the various component parts of the pulp may in an expeditious manner be governed to a nicety, so that each may be conducted away from the concentrating-table without intermixture or combination.

My invention consists in features of novelty hereinafter fully described, and pointed out in the claims.

Figure I is a top or plan view of a concentrating-table and my launder associated therewith, the edges of the table adjacent to the launder being broken away to afford a clear view of the launder. Fig. II is a section taken on line II II, Fig. I, through one of the trough-arms of the launder. Fig. III is a section taken on line III III, Fig. I, through the second launder trough-arm. Fig. IV is a view illustrating a plug by which the passage-ways leading from the launder-troughs may be controlled. Fig. V is a vertical cross-section taken on line V V, Fig. III.

1 designates a concentrating-table, and 2 a feed-box from which the ore-pulp is delivered onto the table for concentration. This table and feed-box form no part of my invention and are illustrated merely for the purpose of showing the application of my launder. The table is designed to receive a flow of water directed thereonto in the usual manner from a suitable wash-water box. (Not shown.)

3 designates the end trough-arm of my launder, which extends beneath the forward end of the concentrating-table 1 to receive the

material passed from the table over that end in the longitudinal reciprocation of the table in the usual manner while acted upon by the wash-water flowing transversely across the table.

4 is the front trough-arm of the launder, which extends beneath the forward edge of the table from a junction with the arm 3. At 60 the inner end of the trough-arm 3 is a conduit 5, which leads to a mineral-conveying pipe 7, (see Fig. III,) through which the free mineral is conducted from the trough-arm after entering thereinto from the rear portion 65 of the concentrating-table.

8 is a shelf located in the trough 3 above the conduit 5 and extending from the partition 10 at the inner termination of the trough-arm 3. In the shelf 8 is an orifice 9, and in 70 the partition 10 above the shelf is an orifice 11. (See Figs. II and III.)

12 is an adjustable slide-trough loosely seated on the end trough 3 and adapted to be moved along said trough to varying positions, 75 with its forward end overhanging the shelf 8, this trough serving to direct the higher grade of middlings onto said shelf 8, and the expanse of table from which it receives discharge is governed by the position of the shelf 80 forwardly or backwardly on the end trough-arm. At the inner end of the front trough-arm 4, which receives the tailings or gangue discharged over the outer portion of the front edge of the table, is a conduit 13, that has 85 communication with a tailings-conveying pipe 14. (See Figs. II and III.) Above the conduit 13 is a shelf 15, that contains an orifice 16 and leads from the vertical partition arranged at right angles to the partition 10 at 90 the inner end of the end trough-arm 3. The partition 17 contains an orifice 18, located above the inner end of the shelf 15. (See Figs. II and III.)

A is a compartment located at the junction 95 of the end and front troughs 3 and 4 and into which communication from the troughs is provided by the orifices 11 and 18 in the partitions 10 and 17.

19 is a middlings-conveying pipe leading 100 from the compartment A.

20 designates an adjustable slide-trough loosely mounted on the front trough 4 and adapted to have its forward end overhang the

shelf 15, as seen in Fig. II. This slide-trough 20 is adapted to receive the low grades of middlings which pass over the front edge of the concentrating-table, and it may be shifted 5 on the front trough to extend a more or less degree over the shelf 15 in order to receive material from a greater or less expanse of the table, according to requirement necessitated to catch the middlings discharged without re- 10 ceiving the tailings which are washed from the table beyond the outer end of said slide-trough.

In the practical use of my launder the table over which the ore-pulp is passed is 15 reciprocated in the usual manner, and during such reciprocation and the usual washing action to which the pulp is subjected the component parts of the pulp are delivered to the launder as follows: The free mineral passes 20 longitudinally off the table and is discharged into the rear or outer end of the end trough 3 and flows downwardly through said trough to escape through the conveying-pipe 7. The tailings are washed forwardly across the ta- 25 ble and enter the outer end of the trough 4 and flow to the conduit 13 and therefrom into the conveying-pipe 14. In treating ore-pulp containing a valuable percentage of middlings of both high and low grades which it 30 is desired to save I close the orifices 9 and 16, located, respectively, in the shelves 8 and 15, by inserting thereinto plugs, such as illus- 35 trated by 21 (see Fig. IV) and shown in dotted lines, Figs. II and III. When the plugs are inserted, as stated, the middlings are dis- 40 charged from the table onto the shelves 8 and 15 and the slide-troughs 12 and 20, that lead thereto. As a consequence the middlings deposited on said shelves are delivered there- 45 from through the orifices 11 and 18 into the compartment A and are conducted there- 50 from through the conveying-pipe 19. (See Fig. II.) In the case of treatment of ore-pulp containing only high-grade middlings I 55 close the orifice 18 and leave the orifice 16 in the shelf 15 open, and thereby permit all of the material passed over the forward part of the table in the vicinity of the shelf 15 to flow through said orifice 16 and discharge 60 with the tailings. In treating ore-pulp of a rich nature and free of high-grade middlings I provide for the discharge of the mineral delivered onto the shelf 8 of the slide-trough 12, leading thereto, by closing the orifice 11, 65 leading into the chamber A, and leave the orifice 9 in the shelf 8 open, so that the mineral delivered to said shelf will pass directly therethrough and enter the conduit 5, to be discharged therefrom through the conveying- pipe 7 with the mineral that enters the rear end of the end trough 3.

In the bottom of the compartment A is an orifice 22, that is designed to be closed by a plug 21 or may be opened to permit the es- 65 cape of the middlings from said compartment

into the conduit 13 of the front or tailings trough 4. At certain times in the use of the launder it may be desirable to divert the middlings into the tailings to avoid cessation of operation of the concentrating-table, this being more liable to be the case in the treatment of the lower grades of ores. The middlings of ore-pulp are usually returned to the concentrating-table after being discharged therefrom, centrifugal pumps being utilized 75 for such return. In the event of the pumps becoming out of order and requiring repairs it would be necessary to stop the operation of the concentrating-table unless the middlings were diverted from their usual discharge in 80 the manner rendered possible by the opening of the orifice 22.

I claim as my invention—

1. The combination with a concentrating-table of a launder comprising a pair of trough-arms provided with mineral and tailings receiving conduits and a middlings-receiving compartment, apertured shelves located in said trough-arms onto which a portion of the substance entering the launder may be conducted either into said middlings-compartment or passed therethrough into said conduits, and means for controlling the flow of the substance from said shelves, substantially as set forth. 95

2. The combination with a concentrating-table, of a launder comprising a pair of trough-arms extending at angles from a juncture with each other and provided with mineral and tailings receiving conduits and a middlings-receiving compartment located at the junction of said trough-arms, apertured shelves located in said trough-arms onto which a portion of the substance entering the launder may be conducted into either said middlings-compartment or passed therethrough into said conduits, and means for controlling the flow of the substance from said shelves, substantially as set forth. 100

3. The combination with a concentrating-table of a launder comprising a pair of trough-arms provided with mineral and tailings receiving conduits and a middlings-receiving compartment, apertured shelves located in said trough-arms onto which a portion of the substance entering the launder may be conducted into either said middlings-compartment or passed therethrough into said conduits, means for controlling the flow of the substance from said shelves, and slide-troughs 115 mounted on said trough-arms above said shelves, said slide-troughs being adapted to receive a portion of the substance passing to the launder and directed onto said shelves, substantially as set forth. 120

JOHN O. BARDILL.
